ELECTRICAL APPARATUS

Hugo Benioff, La Canada, Calif., assignor, by
mesne assignments, to Submarine Signal Com-
pany, Boston, Mass., a corporation of Delaware

Application October 23, 1940, Serial No. 362,434

9 Claims. (Cl. 250—37)

1

The present invention relates to short wave transmitting and receiving systems particularly with spark circuits and electromagnetic waves of the order of one meter or less.

Circuits of this type offer difficulties principally because of the limitations in geometric dimensions that are necessary to keep the natural wave length of the apparatus short. It may be generally stated that the larger the geometrical dimensions of such a device are, the longer the wave length will be at the resonant frequency. It is also essential in such devices, in order to transmit a substantial power, to provide as much storage capacity in the condensers of the oscillating system. Such increase in condenser capacity must, however, be compensated by a decrease in the inductance of the circuit in order to maintain the frequency and wave length at the desired values.

In addition to these features it is also necessary to provide the correct type of spark gap so that a maximum breakdown voltage may be obtained and rapid quenching may be effected. These features work for an increased power and efficiency in the transmitting circuit.

Without further describing the merits of the invention, the present invention will be described in connection with the drawings below illustrating the same.

In the drawings, Fig. 1 shows a vertical section through the transmitting unit; Fig. 2 shows a vertical section through the receiving unit; Fig. 3 shows an isometric projection of the transmitter; Fig. 4 shows a vertical section through another form of the transmitter; Fig. 5 shows an isometric projection of the device a section of which is shown in Fig. 4; Fig. 6 shows the circuit diagram of the generator for the spark potential; Fig. 7 shows in cross section another form of spark generator; Fig. 8 shows an isometric projection of the device, a section of which is shown in Fig. 7; Fig. 9 shows the apparatus of Figs. 7 and 8 as used in a radiating horn; and Fig. 10 shows the electrical circuit diagram for the apparatus of Figs. 7 and 8.

In Figs. 1, 2 and 3 both the receiver and transmitter are of substantially the same external shape. The transmitter comprises two cone elements 1 and 2 which may have rounded ends as indicated at 3 and 4. These cones which are of metal are supported by mounting elements 5 and 6 which are of suitable insulating material. These mounting elements 5 and 6 fit snugly in slots or grooves in the sides of the cones and space the parallel opposing bases 7 and 8 of the cone a desired distance apart. In the center portion of

2

the bases of the cone there are provided circular recesses 9 and 10 with center projecting flanges 11 and 12 on which are mounted points 13 and 14 of tungsten or other suitable alloy or metal, these points being conical in shape and having an angle of approximately 60°. Electrical connections from the generator for the spark potential are made to the cones 1 and 2 at convenient and desirable points.

10 The receiving device, as indicated in Fig. 2, comprises two metallic conical elements 15 and 16 similar to the cones 1 and 2 except that they are joined together in a central section 17. Otherwise the two cones have opposed bases 18 and 19 and are provided at a point near the outside with a hole in which there is screwed a stud 20 having a detector element 21 of silicon, galena or other similar material set in a recess at the end of the stud. On the opposite cone 16 there is mounted in a position opposite to the detector a wire 23 insulated from the cone 16, the wire 23 being adjustable so that it may be positioned at chosen points over the surface of the detector element 21. Each of the cone elements 1, 2, 15 and 16 has a long dimension of substantially a half wave length in the material at the resonant frequency of the oscillator.

In the spark oscillator shown in the figures just described the frequency of oscillation is sufficiently high so that there is very little current penetration internally of the metallic structure. The capacity in the system for the storage of electrostatic energy is made up of the capacities between the two cones 1 and 2 most of which is concentrated between the opposing surfaces 1 and 8. The inductance of the system is also dependent upon the geometric configuration of the conical elements and it may be stated that with larger cones of the same shape the inductance of the system increases accordingly. Other forms of spark oscillators shown in other figures have a greater capacity with the same wave length and in these cases the geometrical configuration of the oscillators have been changed to increase the capacities of the circuit relative to their inductances.

50 In Figs. 4 and 5 there is shown a form of spark transmitter which is adaptable to be enclosed so that the spark itself might be run in a bath of oil or a chamber of gas, air or partial vacuum. In this case the elements 25 and 26 are provided with opposed base surfaces 27 and 28 with central circular recessed portions 29 and 30 having peripheral grooves in which a cylinder or ring 31 of Amphenol, Bakelite, glass or other insulating

material is snugly positioned to form a chamber 32 within the ring. At the center of this chamber each conical metallic element 26 has a metallic insert 33 and 34 set therein with tungsten spark points 35 and 36 at the center thereof opposed to one another. The elements 25 and 26 may be supported and held in positions relative to each other by means of the U-shaped bracket 37 having supporting branches 38 and 39 on which the elements 26 and 25 are respectively mounted. The supporting arms 38 and 39 are made of insulating material as, for instance, Amphenol, or Bakelite, similar to that used for the ring 31. The conical frustum 25 and 26 may be an aluminum compound as, for instance, duraluminum or some other similar type of metal, if desired.

The generating circuit for generating the potential necessary to provide a train of sparks at the desired frequency is shown in Fig. 6. In this case a Tesla type transformer with a thyratron tube in place of spark 48 with primary 41 and high voltage secondary 42 is used, the output being across the secondary 42 to which the tank circuit may be connected.

The primary circuit is completed through one of the condensers C₁, C₂ or C₃ and one of the resistances R₁ to R₅, inclusive, by proper connections of the switches 44 and 45. The condensers C₁, C₂ or C₃ are charged by the direct current high potential source indicated at 46 the negative end of which is grounded and the positive end connected in parallel to one end of all the resistances. The condensers are discharged by means of the thyratron tube 47 the grid of which is biased by the battery 48 in series with a triggering oscillating source 49 which may be sinusoidal peaked or saw-tooth in shape or whatever form is most desirable.

The output of the secondary 42 of the Tesla coil may act as the power source 50 in Fig. 10 which, as indicated in the figure, supplies power preferably through two spark gaps 51 and resistances 52 to the main tank circuit formed by the cones 53 and 54 at the apex of which are the pointed electrodes 55 and 56. The gaps 51 may in some cases be omitted. The type of tank circuit shown in Fig. 10 is more completely illustrated in Figs. 7, 8 and 9. In Figs. 7 and 8 the two spark electrodes 60 and 61 are preferably constructed of tungsten or other metal or alloy with points formed in a 60° cone as a continuation of the metallic cones 62 and 63, respectively. The cones 62 and 63 are made preferably of duraluminum or copper, silver or a plated metal, and have a solid angle of about 60°. These cones are each provided with cylindrical end portions 64 and 65, respectively, in which are grooves or slots 66 and 67 running diametrically across the cylindrical ends. These ends 64 and 65 are supported each by the U-shaped brackets 68 and 69 made of insulating material preferably Amphenol which was previously mentioned. Surrounding the cones 62 and 63 is the conductive shell 70 which is slotted lengthwise at the sides as indicated by the dotted lines 71 and 72 in Fig. 7 to receive the side arms 73 and 74 of the bracket 69, and 75 and 76 of the bracket 68. As each bracket 68 and 69 is held tightly to the cylinder 70 by the tight-fit of the arms 73, 74, 75 and 76 of the bracket, this construction permits the proper adjustment of the sparking points in position with respect to one another. It should also be noted from Fig. 7 that the cylinder 70 is formed as a figure of revolution by the revolution of the half section about the vertical axis through

the spark electrodes. Therefore, the vertical adjustment, as viewed in Fig. 7, of the cones 62 and 63 increases or decreases the conical gaps 77 and 78.

Since in the high frequency apparatus of the present nature the currents and charges are confined to the metallic surfaces, the conical gaps 77 and 78 act like dielectrics of a condenser and it will be seen that for a comparatively short cone, a large capacity is obtained between the cylindrical element 70 and the cones 62 and 63. While the theory of operation is perhaps not completely understood, this construction promotes better oscillating efficiency at very high frequencies.

It should also be observed that the potential varies continually across the gap and in the transient phenomena of the spark discharge, the wave rapidly progresses from the spark gap electrodes 60 and 61 outward in the direction of the elements of the cone. In this way the outward ends 79 and 80 produce radiation in the shape of a ring emanating from the ends of the gap. For this purpose the cones 62 and 63 are made one-half wave length long in the structure not in air. The form shown in Figs. 7 and 8 is preferably used in the horn 81 of Fig. 9 in which the tank spark oscillator is positioned with the cone axis AB transversely positioned in the end of the horn. In this position the radiation from the tank circuit will be in the direction of the axis of the horn indicated by the line CD.

Having now described my invention, I claim:

1. A short wave spark tank circuit oscillator comprising a pair of metallic cones having aligned axes and arranged with the points facing each other, conductive means having a surface surrounding the conical surface of said cones opposed and spaced near thereto and insulating means supporting said cones and said means.

2. A short wave spark tank circuit oscillator comprising a pair of metallic cones of approximately 60° solid angle and arranged with the points thereof facing each other, conductive means surrounding said cones forming an air-gap between the surfaces of said means and said cones and means insulating said cones from each other and said conductive means.

3. A short wave spark resonant tank circuit oscillator comprising means forming a pair of opposed metallic surfaces providing capacity for said resonant circuit having a pair of opposing electrodes projecting centrally from said surfaces, one from each surface, the inductance of the metallic path around the surfaces with the projecting electrodes as the center and said capacity providing the tuning and resonant frequency of the oscillator, and means insulating said metallic surfaces from each other.

4. A short wave spark resonant tank circuit oscillator comprising means forming a pair of opposed metallic surfaces providing capacity for said resonant circuit having a pair of opposing spark electrodes projecting centrally from said surfaces, one from each surface, the inductance of the metallic path around the surfaces with the projecting electrodes as the center and said capacity providing the tuning and resonant frequency of the oscillator, means insulating said metallic surfaces from each other, and means forming a chamber enclosing said spark electrodes.

5. A short wave spark resonant tank circuit oscillator comprising means forming a pair of opposed metallic surfaces providing capacity for said resonant circuit having a pair of opposing

spark electrodes projecting centrally from said surfaces, one from each surface, the inductance of the metallic path around the surfaces with the projecting electrodes as the center and said capacity providing the tuning and resonant frequency of the oscillator, means insulating said metallic surfaces from each other, means forming a chamber enclosing said spark electrodes, said chamber having means increasing the breakdown voltage therein.

6. A short wave spark resonant tank circuit oscillator comprising means forming a pair of opposed metallic surfaces providing capacity for said resonant circuit having a pair of opposing spark electrodes projecting centrally from said surfaces, one from each surface, the inductance of the metallic path around the surfaces with the projecting electrodes as the center and said capacity providing the tuning and resonant frequency of the oscillator, means insulating said metallic surfaces from each other, and means forming a chamber enclosing said spark electrodes, said chamber being partially exhausted of air.

7. A short wave spark resonant tank circuit oscillator comprising means forming a pair of opposed metallic surfaces providing capacity for said resonant circuit having a pair of opposing spark electrodes projecting centrally from said surfaces, one from each surface, the inductance of the metallic path around the surfaces with the

projecting electrodes as the center and said capacity providing the tuning and resonant frequency of the oscillator, means insulating said metallic surfaces from each other, and means forming a chamber enclosing said spark electrodes, said chamber being filled with oil.

8. A short wave spark resonant tank circuit oscillator comprising means forming a pair of opposed metallic surfaces providing capacity for said resonant circuit having a pair of opposing spark electrodes projecting centrally from said surfaces, one from each surface, the inductance of the metallic path around the surfaces with the projecting electrodes as the center and said capacity providing the tuning and resonant frequency of the oscillator, and means insulating said metallic surfaces from each other, said means forming said opposed metallic surfaces having an axis of symmetry of substantially a half wave length at the frequency to be transmitted or received.

9. A short wave spark tank circuit oscillator comprising a pair of metallic surfaces of revolution having aligned axes and arranged within small ends facing each other having spark electrodes at their apices, conductive means having a surface surrounding the surfaces of revolution opposed and spaced near thereto and insulating means supporting said surfaces and said means in said opposed and spaced relation to each other.

HUGO BENIOFF.
